CLAIM

The ornamental design for a support brace for the knee, as shown and described.

DESCRIPTION

FIG. 1 is a perspective view of a support brace for the knee, showing our new design in use;

FIG. 2 is a top plan view of a support brace for the knee, showing our new design;

FIG. 3 is a side view thereof, the other side being a mirror image;

FIG. 4 is a front end view thereof;

FIG. 5 is a rear end view thereof; and,

FIG. 6 is a bottom plan view thereof.

The broken line showing of the lower leg in FIG. 1 is for illustrative purposes only and forms no part of the claimed design. Other broken lines in the drawings indicate stitching.
